US00D552138S

(12) **United States Design Patent** (10) Patent No.: **US D552,138 S**
Kondo et al. (45) Date of Patent: **** Oct. 2, 2007**

(54) **ARM TRANSFERRING SUBSTRATE TO BE PROCESSED**

(75) Inventors: **Masaki Kondo**, Nirasaki (JP);
Tomohiro Abe, Nirasaki (JP)

(73) Assignee: **Tokyo Electron Limited**, Tokyo (JP)

(**) Term: **14 Years**

(21) Appl. No.: **29/245,738**

(22) Filed: **Dec. 29, 2005**

(30) **Foreign Application Priority Data**

Jun. 29, 2005 (JP) 2005-018889

(51) LOC (8) Cl. **15-99**

(52) U.S. Cl. **D15/199**

(58) **Field of Classification Search** D15/199;
15/250.21; 74/490.01; 414/217, 744.3,
414/744.5, 805, 939

(57) **CLAIM**

The ornamental design for an arm transferring substrate to be processed, as shown and described.

DESCRIPTION

FIG. 1 is a front elevational view of an arm transferring substrate to be processed, showing our new design;

FIG. 2 bottom plan view thereof;

FIG. 3 is right side elevational view thereof;

FIG. 4 is a left side elevational view thereof;

FIG. 5 is a top plan view thereof;

FIG. 6 is a rear elevational view thereof; and,

FIG. 7 is a bottom and right front perspective view thereof.
